UNITED STATES PATENT OFFICE.

WILLIAM HENRY HARRISON, OF NEWARK, NEW JERSEY.

VEIL-FASTENER.

SPECIFICATION forming part of Letters Patent No. 506,494, dated October 10, 1893.

Application filed June 21, 1893. Serial No. 478,383. (No model.)

To all whom it may concern:

Be it known that I, WILLIAM HENRY HARRISON, of Newark, in the county of Essex and State of New Jersey, have invented a new and Improved Veil-Fastener, of which the following is a full, clear, and exact description.

The invention relates to buckles, and its object is to provide a new and improved veil fastener, which is simple and durable in construction, readily applied on the ends of the veil to adjust the latter, arranged to greatly facilitate the tying of the veil without danger of accidental unlocking of the fastening members, and at the same time giving all necessary comfort to the wearer and heightening the appearance of the veil on the wearer's head or head-gear, and permitting an instant unfastening of the veil whenever desired, 20 without extra help.

The invention consists of two coupling members, each provided with a loop forming veil-end adjusters, one of the members being provided with an eye having its front bar widened at or near the middle, to be engaged by a hook on the other member, the said hook being formed of curved bars united by a connecting bar formed with an inward bend.

The invention also consists of certain parts 30 and details, and combinations of the same, as will be hereinafter described and then pointed out in the claim.

Reference is to be had to the accompanying drawings forming a part of this specification, 35 in which similar letters of reference indicate corresponding parts in all the figures.

Figure 1 is a reduced perspective view of the improvement as applied. Fig. 2 is a perspective view of the improvement with the 40 veil ends in position, and the coupling members locked. Fig. 3 is a sectional plan view of the same on the line 3—3 of Fig. 2. Fig. 4 is a cross section of the same on the line 4—4 of Fig. 2; and Fig. 5 is a plan view of a 45 modified form of the improvement.

The improved veil fastener A is provided with the two coupling members B and C formed with the loops B' and C' respectively, each having a cross bar B² or C² respectively, 50 on which double the ends D' and D² respectively of the veil D, as plainly shown in Fig.

2, the said ends after passing around the cross bars being passed under the outer part of the loops so that the latter form veil-end adjusters which permit of drawing the veil-ends loose or tight to suit the wearer's convenience. On the release of the extreme ends of the veil the said loops securely hold the ends of the veil in position, as the bars B² and C² in conjunction with the outer ends of the loops, form clamping devices to securely hold the veil ends in place.

On the coupling member B is formed integrally, an eye B³ on which hooks the hook C³ formed integral with the other member C. The eye B³ has its outer bar B⁴ widened at or near the middle, as plainly shown in the drawings, and the hook C³ of the other coupling member is formed with two bars C⁴ and C⁵ bent over in hook fashion and united at their front 70 ends by a transverse bar C⁶ having an inward bend which extends flush with the front face of the bar B⁴ at the time the two members are coupled together and extended in a straight line, as illustrated in Fig. 3. By this special arrangement of the hook end, the two coupling members are not liable to become accidentally unlocked and hence great security is had for fastening the veil in proper 75 position on the head-gear.

In order to unhook the coupling members, the operator shifts or slides the member C over the other member B until the bend in the transverse bar C⁶ has passed the widened portion of the bar B⁴, to enable the operator 85 then to swing the members into an angular position to unhook the hook C³ from the eye B³, by the operator slightly exerting a rearward pressure on the coupling member C.

It is understood that after the coupling 90 members are engaged one with the other, the veil can be drawn tighter, if desired, by adjusting the ends in the loops B or C until the veil is in proper position and sufficiently tight to suit the wearer's convenience. The free 95 ends of the veil are then tied over the veil fastener so that the latter is completely hidden, and hence not visible.

It will be seen that the device is very simple and durable in construction, and permits 100 of readily adjusting the veil to hold the same in proper position without additional aid.

The device also permits of an instant unfastening of the veil whenever desired, by the operator simply disconnecting the two coupling members by unhooking the hook C³ from the eye B³, as above described.

5 The device obviates the use of pins, which frequently tear the veil and are not always on hand when wanted.

The fastener permits of using the veil for 10 all kinds of hats.

As illustrated in Fig. 5 the division bar between the eye and loop in the member B is 15 omitted and likewise the bar between the inner ends of the bars C⁴ and C⁵ is dispensed with; otherwise the buckle is the same as above described in reference to the other figures.

Having thus fully described my invention,

I claim as new and desire to secure by Letters Patent—

20 A veil fastener, comprising two coupling members, each provided with a loop having a cross bar to form a veil end adjuster, one of the said members being provided with an eye having its front bar widened at or near 25 the middle, and a hook on the other coupling member to engage the said eye, the said hook being formed of two curved bars united at their free ends by a cross bar formed with an inward bend, substantially as shown and de- 30 scribed.

WILLIAM HENRY HARRISON.
